FIG. VI.

FIG. VII.

UNITED STATES PATENT OFFICE.

HOMER D. KRAMER, OF PITTSBURGH, PENNSYLVANIA.

SWEATBAND FOR HATS.

Application filed August 2, 1923. Serial No. 655,185.

To all whom it may concern:

Be it known that I, HOMER D. KRAMER, residing at Pittsburgh, in the county of Allegheny and State of Pennsylvania, a citizen of the United States, have invented or discovered certain new and useful Improvements in Sweatbands for Hats, of which improvements the following is a specification.

10 My invention relates to the sweat-bands of hats, and is found in a pneumatic band of particular structure and arrangement. The band of my invention possesses the manifestly desirable characteristics of a 15 pneumatic band in a form and in combination with accessory structural features, such as to render it in every respect adequate and desirable.

The invention is illustrated in the accompanying drawings. Fig. I is a view in vertical and medial section of a hat having applied to it the sweat-band of my invention. Fig. II is a view in horizontal section, on the plane indicated at II-II, Fig. 25 I. Figs. III and IV are fragmentary views to larger scale, showing in horizontal section and in elevation a portion of the band, and illustrating features of structure and the method of attachment to the hat. Figs. 30 V and VI show in elevation and in horizontal section an alternative arrangement. Figs. VII and VIII show in side elevation and in vertical section another alternative. Fig. IX is a view similar to Fig. III, illustrating a modification.

The sweat-band includes, first of all, a foundation stiffener 1. This stiffener is formed of material of suitable rigidity and lightness, and is adapted to serve in association with the other parts in the manner I am about to describe. A suitable material is fibre board three one-hundred-and-twenty-eighths of an inch in thickness. The width of the stiffener may vary, according to 40 circumstances, but ordinarily a width of seven eighths of an inch is proper. The stiffener will ordinarily be made in two sections, each of approximately semi-circumferential extent with respect to the hat. 45 Preferably the lengths will be slightly less than semi-circumferential, leaving, when the band is applied, spaces between the ends of the sections, and into these spaces shorter lengths of similar material will be introduced. So that all told there are in the

completed sweat-band four lengths of fibre board or its equivalent. The edges of the stiffener are rounded, so that there will be no danger of abrading or tearing the rubber parts with which, as presently will be explained, the stiffener is associated. And holes are formed through the stiffener, into which the fastening means are introduced.

The stiffener 1 is, on one side at least (on the side toward the wearer), faced with an extensible pneumatic bag or cover. Conveniently and economically the stiffener 1 is enclosed and encased, as the drawings show it to be, in an expansible rubber tube 2. The size of the tube is preferably such that, when in place and not inflated, it fits snug upon the stiffener within. The rubber then may or may not be under slight tension. The thickness of the tube wall and the elasticity of the rubber used will be carefully adapted to the end in view. Ordinarily, with rubber of elasticity approaching that ordinarily used for such purposes, the thickness will approximate that of the stiffener.

The stiffener so encased in rubber is anchored firmly, and by its anchoring is held snug against the inner wall of the hat. Several alternative methods of anchoring will presently be particularly described.

The tube 2 which encloses the stiffener 1 is provided with an inflation tube 3, and when the band has been applied, the tube 2 is by such means inflated. The anchoring means hold the stiffener snug against the wall of the hat (with a wall of rubber between), and the inflation will consist in a bulging or bellying out of the tube on the inside only, on the side which in use engages the head of the wearer, as indicated in Figs. I, II, III, and VI.

Means of attachment of stiffener 1 to hat wall 4 as shown in Figs. III and IV consist of a flexible tongue 5 of suitable metal, aluminum say, riveted to stiffener 1 on its outer side, and through the outer wall of the enveloping tube 2. A plurality of such tongues are secured to each stiffener. As I have said, I preferably employ two stiffeners in making the band of a hat, the two stiffeners being of equal length, each approximately a half of the whole circumferential extent of the hat. With two stiffeners of approximately semi-circumferential extent, 105

I provide two or more tongues for each, secured near the ends of the stiffeners (additional tongues may be secured at intermediate points). In making application the 5 tongues initially extend at right angles to the sweat-band, the band is brought to place, and the tongues are thrust through the hat wall, and then are bent smooth beneath the outer band 6 of the hat. In securing the 10 sweat-band the stiff material is warped until it lies snug against the inner wall of the hat and the band is then secured. The anchoring is firm, and the rigidity of the material is such that the stiffener lies snug 15 along the hat wall, with a layer of rubber between, and inflation, when effected, occurs substantially all on the inner face of the sweat-band. The riveting through is made air-tight, in consequence of the incidental 20 compression exerted upon the edges, where the rubber is pierced by the rivet. Thus the desired pneumatic effect is got in a minimum space between the wearer's head and the wall of the hat, and clumsiness of appearance 25 is avoided.

It is a simple matter to stretch the rubber of tube 2 at the ends somewhat, and so expose the strip for riveting in the manner shown in Fig. III. Instead, and as shown 30 in Figs. V and VI, the riveting may be effected through both walls of the tube. The breaking of the crowned edge of the rivet, in the familiar manner indicated in Fig. V, may in the structure of Fig. III be found 35 undesirable, in that the relatively sharp corners may be a source of danger in the tearing of the rubber. It is a simple matter to select rivets of soft metal, so that the edges of the crown formed in riveting will not 40 split but remain continuous. The tongue 5 is, as best shown in Fig. V, preferably formed as an extension from a body which encircles the rivet and constitutes a washer or collar, to make the joint smooth and airtight. 45

Still other means of anchoring are illustrated in Figs. VII and VIII. Here a staple 7 is provided whose prongs are driven through the walls of the hat from the outside, and beneath the hat band. The spread of the staples is equal to the width of the sweat band. The prongs of the staple are provided with securing protrusions, indicated at 8. The staples are initially thrust 55 through the hat walls at the proper points. The sweat band is then brought to place. Thereupon the prongs of the staples are folded down over the inner face of the sweat band, and sufficient pressure is applied to 60 impress the protrusions 8 into the sweat band, and, compressing the rubber wall between, into recesses which may be formed for the purpose in the stiffener 1. Thus firm anchorage is got.

65 At the ends I close the tube 2, to form a

closed and inflatable sack. As shown in Figs. II and III closure of the ends is effected by cementing or vulcanizing, or both cementing and vulcanizing, the tube within to the surface of the stiffener which it envelopes. The stiffener thus is held securely within the rubber tube and there is no possibility that the rubber may be cut by the corners of the stiffener. As shown in Figs. 70 V and VI the tube is somewhat longer than the stiffener, and the tube walls are united 75 face to face, beyond the end of the stiffener.

I have said that I prefer to form the stiffeners 1 in two semi-circumferential halves. Correspondingly I provide two 80 lengths of tube, each of approximately equal length with a stiffener, and, with attention fixed particularly on Fig. II, I then have short intervals, oppositely arranged, at front and back, where the band is not inflatable. The band being elsewhere inflated, these intervals afford spaces for air circulation, and constitute the hat a cooler hat for the wearer. Of course such circulation 85 spaces may be provided, even though the sweat band be formed in a continuous circumferential piece, but the two-piece structure makes the provision of circulation spaces simple and is otherwise preferable. 90 These circulation spaces may be made wide 95 or narrow, as preferred.

I have said also that while I make the stiffeners each of approximately semi-circumferential length, I prefer to make them 100 something less than that and to bridge the gap between with shorter lengths of fibre board. This refinement is shown in Figs. III and IV. Here a short length of fibre board 10 is interposed between the ends of the two stiffeners 1 which together constitute 105 the foundation of the sweat-band as a whole, and the end of the tube, extended cuff-like beyond the region of closure, encloses the interposed length 10 of fibre board. It will be understood that in making application of the sweat-band to a particular hat the length 10 of fibre board may be trimmed 110 accurately to size; that the cuff extending from one or both sections of the two-part sweat-band may be correspondingly trimmed; and that the length of fibre board 10 so inserted may when in place be stitched to or otherwise secured to the wall of the hat. The cuffs which enclose the inserted length 10 are of course not inflated.

By such means I provide for nice adjustment in applying the sweat-band to the hat; and I provide also for a relatively wide ventilation space, which I find advantageous. I intend that this ventilation space shall be 115 from one to three inches wide, measured in the direction of the circumference. This interposed piece 1 preferably of fibre board somewhat thinner than that of which the stiffeners are formed. This I may do 120 125 130

without impairing its usefulness as a bracing member, and at the same time by so doing I increase the depth of the ventilating space.

The length of fibre board 10 introduced 5 between the ends of the stiffeners 1 and enclosed within the extended cuffs of rubber at the ends of the tube sections 2 affords a brace, and is particularly useful when the sweat-band is applied to a soft hat. Various 10 modifications in detail are admissible. For instance, as particularly shown in Fig. IX the structure resembles that of Fig. III. The cuff-like extensions of the rubber tubes, however, are not present, but the tube sections 15 2 are trimmed flush with the stiffeners 1. The inserted length of fibre board 10 which bridges the gap between the ends of the sweat-band sections is braced, not as in Fig. III against the ends of the stiffeners 1, 20 but it underlies the ends of the stiffeners and the ends of the tube sections also, and is braced against the rivets by which the tongues 5 are anchored. A separate tube section 11 encases the inserted length 10 of 25 fibre board and overlaps the ends of the sweat-band sections. This tube section is of course not inflated.

It will be understood in considering Fig. IX that in thickness the dimensions are for 30 the sake of clear showing exaggerated, and that in fact the finish of the structure is much smoother than the figure might lead one to understand.

If it be desired to make the ventilation 35 space deeper, the ply of rubber adjacent the hat-wall may be cut away, and the otherwise free edges of the rubber secured to the inserted length of fibre board.

If the hat have a lining the inflation 40 tubes 3 may, after inflation be tucked out of sight behind the lining.

Operation is obvious. The sweat-band 45 when applied in the manner described stands ready for inflation, and the hat which approximately fits may by inflation to greater or less degree be made to fit accurately.

Ordinarily the range of inflation will be 50 from a sixteenth to an eighth of an inch. The hat may then be accurately fitted to the head. It is comfortable to wear, the feature of inflation giving exceptional comfort. The hat provided with this sweat-band will not impress a mark upon the forehead. The hat may be pressed tight on the 55 head and may not then easily be blown off. The ventilation afforded by the uninflated spaces is effective beyond any ordinary provision to that end. The band may

be kept clean. The material is not hydroscopic and it accordingly protects the hat against fouling and staining by sweat.

Superiority over other inflated bands lies in this, that inflation effects bellying of the band in one direction only, that is inward, and in consequence the desired good effect can be got within a space interval half of what otherwise would be required, and so the appearance of the hat when worn is trim and neat, as otherwise would not be the case.

I claim as my invention:

1. An inflatable sweat-band for hats, including in combination a stiffener of rigid material and a sack of elastic and expandable material enclosing said stiffener, the structure adapted to be secured when deflated in close parallelism to the wall of a hat and when so secured adapted on inflation to present an inwardly bellied pneumatic cushion for engagement with the head of the wearer.

2. An inflatable sweat-band for hats including in combination a stiffener of rigid material and a closed sack of elastic and expandable material enclosing said stiffener, and tongues of flexible metal protruding from the band at intervals, said tongues being anchored through the wall of said sack and to said strip, the penetration of the anchoring means through the sack-wall being air tight.

3. An inflatable sweat-band for hats including in combination a stiffener of rigid material and a closed sack of elastic and expandable material enclosing said stiffener, annular collars provided each with a flexible tongue, and a rivet extending through each ring and securing each tongue-bearing ring to the stiffener.

4. An inflatable sweat-band for hats formed of two stiffeners of rigid material, each of substantially semi-circumferential length, said sweat-band including a pneumatic sack closed terminally enclosing each of said stiffeners, each stiffener provided adjacent its ends with anchoring means, the pneumatic sacks at each end extending beyond the point of closure in the form of joint-forming cuffs, and bridge pieces enclosed by such cuffs.

In testimony whereof I have hereunto set my hand.

HOMER D. KRAMER.
